DESIGN FOR A DOLL

Edith Blanche Groshong, Eureka, Calif.

Application March 12, 1946, Serial No. 127,394

Term of patent 7 years

(Cl. D34—4)

To all whom it may concern:

Be it known that I, Edith Blanche Groshong, a citizen of the United States of America, residing at Eureka, in the county of Humboldt and State of California, have invented a new, original, and ornamental Design for a Doll, of which the following is a specification, reference being made to the accompanying drawing, forming a part thereof, wherein:

I claim:

The ornamental design for a doll, as shown.

EDITH BLANCHE GROSHONG.
